UNITED STATES PATENT OFFICE.

CARL H. BLOMSTROM, OF MARQUETTE, MICHIGAN, ASSIGNOR TO THE LAKE SHORE ENGINE WORKS, OF SAME PLACE.

GEAR MECHANISM.

SPECIFICATION forming part of Letters Patent No. 657,057, dated August 28, 1900.

Application filed February 26, 1900. Serial No. 6,470. (No model.)

To all whom it may concern:

Be it known that I, CARL H. BLOMSTROM, a resident of Marquette, county of Marquette, State of Michigan, have invented certain new and useful Improvements in Gear Mechanism, of which the following is a full, clear, and exact description.

This invention has relation more especially to that class of gearing in which provision is made whereby the mechanism or part driven may be caused to move either in the same direction as the drive-shaft leading from the engine or in a direction opposite to the direction of revolution of the drive-shaft or in which the driven part or mechanism may be maintained in a condition of rest without the stoppage of the drive-shaft.

My invention as embodied in the accompanying drawings is particularly well adapted for communicating motion to the propeller of a boat from an explosive or like engine, since it affords a means whereby the continuous movement of the drive-shaft in the same direction may be caused to impart movement either in the same or opposite directions to the propeller shaft, or by bringing the gearing to a neutral position the propeller-shaft will remain at rest.

While I have shown in the accompanying drawings what I regard as the preferred embodiment of my invention, it is manifest that the invention may be widely modified without departure from the spirit thereof, and I do not wish the invention to be understood as restricted to the precise details of construction hereinafter described.

Figure 1 is a view in side elevation of an improved gearing embodying my invention, the inclosing casing being shown in central vertical section. Fig. 2 is a view in vertical longitudinal section through the casing and mechanism contained therein. Fig. 3 is a view in cross-section on line 3 3 of Fig. 1. Fig. 4 is a view in central horizontal section, the upper part of the inclosing casing being removed. Fig. 5 is a detail plan view, parts being shown in section, of the gear mechanism within the casing. Fig. 6 is a detail plan view of one of the washers. Fig. 7 is a detail side view of one of the clutch-shoes. Fig. 8 is a detail face view of one of said shoes.

Fig. 9 is a view in vertical cross-section through one of the screw-pinions. Fig. 10 is a detail view, in side elevation, of the screw-stud.

My improved mechanism is preferably inclosed within a casing that is formed of the sections A and A', these sections being provided with suitable flanges whereby they may be bolted together, as at a, and the section A being formed with an expanded base a'. At one end of the casing formed of the sections A and A' is an opening through which passes the drive-shaft B, and at the opposite end of the casing is formed an opening through which passes the driven shaft C. The inner end of the shaft B has keyed thereto a gear-wheel b, and in like manner the inner end of the shaft C has keyed thereto a similar gear-wheel c. The extreme inner ends of the shafts B and C set within suitable seats formed in a hub D, through which hub passes a cross shaft or axle E, that is keyed to the hub D, so that it will partake of the revolution of the hub, but will have no independent revolution with respect thereto. Upon the opposite ends of the cross shaft or axle E are loosely mounted coupling-gears F and F', the teeth of which mesh with the gears b and c on the drive-shaft and the driven shaft. Each end of the axle or cross shaft E is formed with a thread e, with which engages a corresponding thread g, formed upon the interior of a pinion G. The pinion G has its hub provided with an annular groove g', adapted to receive a pin h, that projects inwardly from the side wall h', that overlaps the hub of the wheel G and is formed on a shoe H. By reference to Figs. 7 and 8 the construction of the shoes H will be seen, and it will be observed that each of the shoes is formed with a hole h², through which passes a screw h³, the reduced threaded end of which enters a threaded seat in the corresponding end of the cross-shaft E, the purpose of this screw h³ being to retain the shoe against lateral movement, while permitting it to move to a limited extent in the direction of the length of the shaft E. Each of the shoes H has a curved bearing-surface, adapted to engage a corresponding surface a², formed upon the interior of the casing-sections A and A'.

Between each of the pinions G and adjacent the coupling-gear F is interposed a washer K, that is held in manner free to move lengthwise of the shaft E, but against revolution, 5 by a pin k, projecting from the shaft and entering a slot in the washer. The hub D is shown as provided with extensions D', from which project outwardly the arms or rods D², that enter corresponding holes formed in a 10 disk M, that projects radially from a collar M', loosely mounted on the shaft B. This collar M' is shown as formed with an annular groove to receive a ring m, to the trunnion-pins m' of which is pivotally connected the 15 yoke-shaped shifter-lever N, that is pivoted, as at n, to a bracket a⁵, projecting outwardly from one end of the inclosing casing. By means of the lever N the collar M' and disk M may be shifted back and forth for the purpose 20 to be presently stated. From the disk M project inwardly the rack-bars M² and M³, that engage the pinions G at the opposite ends of the cross-shaft E, and by shifting the collar M' and disk M a partial revolution will 25 be imparted to the pinions G, so as to cause these pinions to force the coupling-gears F and F' to bear upon the hub D or to release the gears F and F' from the hub D and force the shoes H against the bearing-surface a² of 30 the inclosing casing, or by the shift of the disk M the pinions G may be brought to neutral position, at which point the coupling-gears F F' will be disengaged from the hub D and the shoes H will be disengaged from 35 the bearing-surface a² of the inclosing casing.

From the foregoing description it will be seen that when the shifting-lever N is moved to the position shown in Figs. 1 and 2 of the drawings the inward movement of the lever 40 N and collar M' will be such as to cause the rack-bars M² and M³ to so turn the pinions G as to force the coupling-gears F F' into firm engagement with the hub D, so that these gears F F' are no longer free to revolve. Now, 45 inasmuch as the gears F F' are in engagement with the gear-wheels b and c, it is manifest that if revolution be imparted to the drive-shaft B then revolution in like direction will be imparted to the driven shaft C. If now, 50 however, it is desired to reverse the direction of revolution of the driven shaft C, the operator will shift the lever N so as to force the collar M' and disk M to its extreme outward position—that is to say, in position the reverse of that illustrated in Figs 1 and 2 of the 55 drawings. As the disk M is moved to such position the rack-bars M² and M³ will impart partial revolution to their corresponding pinions G, thereby causing these pinions to move 60 outward and to force the shoes H into firm bearing with the surfaces a² of the inclosing casing. This engagement of the shoes H with the bearing-surface a² will hold the shoes and shaft E against revolution, while at the same 65 time the coupling-gears F F' are left free to revolve upon the cross-shaft E. Hence it will be seen that if revolution be given to the drive-

shaft B it will be transmitted through the gear-wheel b, coupling-gears F F', and gear-wheel c to the driven shaft C, thereby revolving said drive-shaft in opposite direction. If now it is desired to allow the driven shaft C or part of the mechanism connected therewith (such, for example, as a propeller-wheel) to remain stationary, then the operator will 70 shift the lever N to such extent as will bring the disk M and collar M' to a point midway between extreme positions. This will have the effect of turning the pinions G such distance as to relieve the shoes H from engagement with the bearing-surface a² of the inclosing casing, while at the same time leaving the coupling-gears F F' disconnected from the hub D and free to revolve upon the shaft E. Assuming, therefore, that there is slight 75 resistance upon the driven shaft C, it will be seen that when revolution is imparted to the drive-shaft B the coupling-gears F F' and hub D will merely revolve and travel orbitally without imparting revolution to the driven 80 shaft C.

It will be observed that the shoes H are cut away, as at h⁴, to engage correspondingly-cut-away portions d⁴ of the hub extensions D', the purpose of this arrangement being to 85 better hold the shoes against displacement. The driven shaft C is shown as passing through bearing-rings R and S S', between which bearing-rings are interposed ball-bearings T, that are held within annular grooves formed upon the opposing faces of the rings. The ring R is connected by a set-screw r to the shaft C, while the rings S S' loosely encircle the shaft and are held stationary. The rings R, S, and S' are contained within a cap W, that is connected by a threaded joint w to the correspondingly-threaded flange or extension a⁶, around the central opening of the inclosing casing. A lock-nut Y is also mounted upon the threaded flange or extension of the casing, the purpose of this lock-nut being to retain the cap W in any position at which it may be set. It will readily be seen that when wear occurs between the rings R, S, and S' such wear may be taken up by an adjustment 105 of the cap W, and when properly adjusted the cap will be held in fixed position by means of the lock-nut Y.

It is obvious not only that the precise details of construction above set out may be 110 varied without departing from the spirit of the invention, but that features of the invention may be adopted without its employment as an entirety.

Having thus described my invention, what I claim as new, and desire to secure by Letters Patent, is—

1. A gear mechanism for connecting a driving shaft or part and a driven shaft or part, comprising a gear-wheel united to the driving shaft or part, a gear-wheel united to the driven shaft or part, a coupling-gear connecting said above-mentioned gear-wheels, a hub or support interposed between said driving

and said driven shafts or parts and whereby said coupling-gear is sustained, mechanism for directly locking said coupling-gear to said hub or support to prevent the revolution of said gear about its own axis and for freeing said coupling-gear whereby said driving and said driven shafts or parts may be caused to revolve or not to revolve in the same direction.

2. A gear mechanism for connecting a driving shaft or part and a driven shaft or part, comprising a gear-wheel united to the driving shaft or part, a gear-wheel united to the driven shaft or part, two oppositely-disposed coupling-gears connecting said above-mentioned gears, a hub or support interposed between said coupling-gears and between said driving and said driven shafts or parts, and whereby said coupling-gears are pivotally sustained, mechanism for directly locking said coupling-gears to said hub or support to prevent their revolution about their own axes and for freeing said coupling-gears in order to allow them to revolve.

3. A gear mechanism for connecting a driving shaft or part and a driven shaft or part, comprising a gear-wheel united to the driving shaft or part, a gear-wheel united to the driven shaft or part, a coupling-gear connecting said above-mentioned gear-wheels, a hub or support interposed between said driving and said driven shafts or parts and whereby said coupling-gear is sustained, mechanism for directly locking said coupling-gear to said hub or support to prevent the revolution of said gear about its own axis and for freeing said coupling-gear, and for directly locking said hub or support against revolution.

4. A gear mechanism for connecting a driving shaft or part and a driven shaft or part, comprising a gear-wheel united to the driving shaft or part, a gear-wheel united to the driven shaft or part, a coupling-gear connecting said above-mentioned gear-wheels, a hub or support interposed between said driving and said driven shafts or parts and whereby said coupling-gear is sustained, said hub or support being provided with one or more movable shoes, a stationary brake member adapted to be engaged by said shoe or shoes, mechanism for locking said coupling-gear to said hub or support to prevent the revolution of said gear about its own axis, and for releasing said coupling-gear and for moving said brake shoe or shoes against said brake member to arrest the movement of said hub or support.

5. A gear mechanism for connecting a driving shaft or part and a driven shaft or part, comprising a gear-wheel united to the driving shaft or part, a gear-wheel united to the driven shaft or part, a coupling-gear connecting said above-mentioned gear-wheels, a hub or support interposed between said driving and said driven shafts or parts and whereby said coupling-gear is sustained, said hub or support being provided with an axle whereon said coupling-gear is pivotally

mounted and upon which axle said coupling-gear is mounted in manner free to slide into and out of engagement with said hub or support, a movable brake-shoe carried by said hub or support and mechanism for locking said coupling-gear to said hub and for releasing said coupling-gear from engagement with said hub or support and for checking the movement of said brake-shoe.

6. A gear mechanism for connecting a driving shaft or part and a driven shaft or part, comprising a beveled gear-wheel united to the driving shaft or part, a beveled gear-wheel united to the driven shaft or part, said gear-wheels being mounted to revolve in parallel planes, two coupling-gears connecting said above-mentioned gear-wheels, a hub or support interposed between said gear-wheels and said coupling-gears and provided with axles whereon said coupling-gears are journaled in manner free to revolve and to slide lengthwise thereof, means for locking said coupling-gears to said hub or support and for releasing said coupling-gears therefrom, and means for arresting the motion of said hub or support while allowing the coupling-gears to revolve upon their own axes.

7. A gear mechanism for connecting a driving shaft or part and a driven shaft or part, comprising a gear-wheel united to the driving shaft or part, a gear-wheel united to the driven shaft or part, a coupling-gear connecting said above-mentioned gear-wheels, a hub or support interposed between said driving and said driven shafts or parts, said hub or support being provided with a screw-threaded shaft or axle whereon said coupling-gear is mounted in manner free to revolve and to move lengthwise thereof, a screw-threaded wheel mounted upon said axle and means for revolving said screw-threaded wheel in order to shift said coupling-gear upon its axle to effect the locking of said coupling-gear to said hub or support.

8. A gear mechanism for connecting a driving shaft or part and a driven shaft or part, comprising a gear-wheel united to the driving shaft or part, a gear-wheel united to the driven shaft or part, a coupling-gear connecting said above-mentioned gear-wheels, a hub or support interposed between said driving and said driven shafts or parts, said hub or support being provided with a screw-threaded axle or shaft whereon said coupling-gear is mounted in manner free to revolve and to move lengthwise thereof, a screw-threaded pinion mounted upon said threaded axle, a rack-bar engaging said pinion, and shifting mechanism for operating said rack-bar and pinion in order to move said coupling-gear into and out of engagement with said hub or support.

9. A gear mechanism for connecting a driving shaft or part and a driven shaft or part, comprising a gear-wheel united to the driving shaft or part, a gear-wheel united to the driven shaft or part, a coupling-gear connecting said

above-mentioned gear-wheels, a hub or support interposed between said driving and said driven shafts or parts, said hub or support being provided with a threaded axle 5 whereon said coupling-gear is mounted in manner free to revolve and to slide lengthwise thereof, a screw-threaded pinion carried by said axle, a brake-shoe connected to said pinion, a shiftable rack for turning said pinion 10 in order to effect the engagement and disengagement of said coupling-gear with said hub or support, and a stationary brake member against which said brake-shoe may be forced by said pinion.

15 10. A gear mechanism for uniting a driving shaft or part and a driven shaft or part comprising two beveled gear-wheels arranged to revolve in parallel planes and connected respectively to the driving and the driven shafts 20 or parts, two beveled coupling-gears uniting said gear-wheels, a hub or support arranged between said gear-wheels and said coupling-gears and provided with a threaded axle or shaft whereon each of said coupling-gears is 25 revolvably and axially movable, screw-threaded pinions mounted upon said shaft outside of said coupling-gears and whereby said gears will be shifted, brake-shoes connected to said pinions, a stationary brake member with which 30 said brake-shoes may engage, rack-bars en-

gaging said pinions and a revoluble shifting device carrying said rack-bars and connected with said hub or support.

11. A gear mechanism for uniting a driving shaft or part and a driven shaft or part, comprising two beveled gear-wheels arranged to revolve in parallel planes and connected respectively to the driving and the driven shafts or parts, two beveled coupling-gears uniting said gear-wheels, a hub or support arranged 35 between said gear-wheels and said coupling-gears and provided with a threaded axle or shaft whereon each of said coupling-gears is revolvably and axially movable, screw-threaded pinions mounted upon said shaft outside 40 of said coupling-gears and whereby said gears will be shifted, brake-shoes connected to said pinions, a stationary brake member with which said brake-shoes may engage, rack-bars engaging said pinions and a revoluble shifting device carrying said rack-bars and connected with said hub or support, said shifting device comprising a slidable sleeve mounted upon the driving-shaft and provided at its inner end with a lateral disk or extension carrying 45 said rack-bars.
